JAMES P. SCOVILL, OF TROY, NEW YORK, ASSIGNOR TO PEERLESS MACHINE CORPORATION, OF NEW YORK, N. Y., A CORPORATION OF DELAWARE.

TOBACCO-STRIPPING MACHINE.

Application filed April 24, 1925. Serial No. 25,517.

This invention is an improvement in tobacco stripping machines, and more particularly in machines for stripping the lamina from the stem cleanly and in relatively 5 large pieces.

In the usual construction of stripping or stemming machine of this character the leaf is grasped by the butt of the stem, and moved through stemming devices, which 10 strip the lamina from the stem while it is so held. The lamina does not strip readily in this direction, for several reasons, among which, may be mentioned the disposition of the stem branches, and the close tenacious 15 union between the lamina and the stem at the point where the side edges of the lamina merge into the stem, near the butt.

At this point the union between the stem and the leaf is strong and tough offering a 20 relatively large tensile resistance to any stress tending toward separation of the lamina and stem. It is impracticable however, to strip toward the butt. The tip of the stem is not strong enough to withstand 25 the pulling stress of the stripping operation, and moreover since a relatively large part of the finer stem portion is capable of utilization for all purposes for which the leaf is used, it is desirable that in the stripping 30 operation a portion of the stem tip be left with the stripped lamina, and that this portion of the leaf be exposed to as little chance of mutilation as possible in the stripping operation.

35 In stripping or stemming machines where- in the stem butt is held during the stripping operation, there is usually a relatively large proportion of drops, that is of leaves not tightly enough grasped by the transporting 40 means to resist the pull of the stripping devices, and which pass through the machine unchanged, to be later stripped manually or in some other manner.

45 Since the leaves at the time of stripping are carefully conditioned, usually by steam treatment, to bring them into proper "case" for the separation of the lamina and stem without breaking or shattering fragmentation of the leaf, it is desirable that the stripping operation be as nearly complete as possible while the tobacco is in such a condition, and that the dropping of the leaves from any cause be avoided, or at least 50 greatly limited.

It is also desirable that the stripping operation be as nearly as possible in one direction, and substantially continuous, and while the leaf is grasped by a single grasping means, so far at least as concerns the stripping of the body portion of the leaf, thus 55 to avoid the liability to breakage of the stem from re-handling.

The stripping operation is usually performed by cooperating leaf transporting 60 mechanism and stripping devices, which operate on diverging lines, so that while the leaf is moved laterally by the transporting means, there is in addition relative movement of the leaf and stripping devices longitudinally of the leaf.

70 With such an arrangement, the action of the stripping devices, upon the closely adherent portion of the lamina at the butt is not sufficiently violent nor of a duration to efficiently break this connection.

75 An object of the present invention is the provision of a machine having means to primarily break the lamina transversely of the leaf on each side of the stem, near the butt, prior to the stripping operation.

80 Another object is the provision in such a machine of mechanism operating along a selected line transversely of the leaf over a length of time, and with a sufficient violent action to thoroughly break up the strong 85 connection between the leaf and the stem near the butt.

85 Another object is the provision of mechanism for more firmly grasping the butts of the stems as they are fed through the machine, thereby to reduce the proportion of drops.

To the accomplishment of the foregoing and such other objects as may hereinafter appear, the invention consists in the construction and novel combination of parts fully described hereinafter, illustrated in the accompanying drawings, and pointed out in the claims appended hereto, it being understood that various changes in the form, 90 proportion, size and minor details of construction within the scope of the claims, may be resorted to without departing from the spirit of the invention.

In the drawings:

Fig. 1 is a plan view of the improved machine.

Fig. 2 is a section on the line 2—2 of Fig. 1.

Figs. 3, 4, and 5 are plan views of a leaf showing its condition at the end of the several stages of the operation.

Figs. 6 and 7 are sections on the line 6—6 and 7—7 respectively, of Fig. 2.

In the present embodiment of the invention, a suitable supporting frame 1 is provided, having at one end an extension 2, in which is journaled a pair of rollers 3 and 4, and an endless feed belt 5 is supported by the rollers 3 and 4. The upper run of the said belt moves over a table 6 which is adjustably mounted on laterally extending arms 7 from the extension, the adjustment being provided by slot and screw connections indicated at 8. This table carries at the edge adjacent to the extension 2, a butt plate 9, in the form of an upstanding flange, against which the leaves are butted, as they are moved over the table by the feed belt.

As the leaves leave the feed belt 5, they are delivered to the transporting mechanism, which carries them past the stripping devices. The transporting mechanism in the present instance is constituted by a pair of upper and lower chains 10 and 11 respectively, the chains being so arranged that the lower run of the upper chain and the upper run of the lower chain move in contact along a horizontal line, parallel with the length of the butt plate 9.

The lower chain is supported by sprocket wheels on shafts 12 and 13 respectively, the former being journaled transversely of the main frame 1, and on the rear end thereof, while the latter is a stub shaft journaled in the extension 2. This chain is driven in a manner to be presently described, and it in turn drives the upper chain, which is supported by sprocket wheels on shafts 14 and 15, the former being just above the shaft 12 while the latter is above and in rear of the stub shaft 13. The upper chain is tensioned by means of a wheel 16 carried by a plate 17, which is adjustably connected to a bracket 18 extending upwardly from the main frame. The adjustment is provided by means of a slot in the plate, and a bolt on the bracket, the parts indicated at 19.

The stub shaft 13 also drives the feed belt 5 through a sprocket chain 20 mounted on sprockets on the stub shaft and on the shaft 3 respectively, and the upper run of the chain is supported by a grooved roller 21 connected with the extension 2. The shaft 3 is adjustable longitudinally of the extension. Referring to Fig. 2, it will be seen that the extension is longitudinally slotted at 22 to receive the shaft, and that a plate 23 mounted on the shaft is adjustably connected with the extension. The plate has bolts at its ends, which move in slots 24 in the extension, and it will be evident that when the bolts are tightened, the shaft 65 will be anchored in adjusted position, it be-

ing understood that the shaft is rotatably connected with the plate.

Referring to Fig. 2 it will be seen that the chains 10 and 11 are similarly constructed, all of the links of each chain being arched in the same direction. The links are arcs from pivot to pivot, and all of the links of each chain are similarly arranged. With both chains, the concavities of the arcs are outward, and from this arrangement results that on the cooperating runs of the chains the concavities of the links of the two chains face each other, and the runs are so spaced that the convex portions of each chain, that is the pivoted ends of the links will engage within the concave portions of the other chain. Thus there is a close engagement throughout the length of the runs and a positive driving connection between the lower and the upper chain.

The chains 10 and 11, as before stated, constitute the transporting mechanism for the leaves, to carry them past the stripping devices, which in the present instance are composed of upper and lower rotating members having their axes in the same vertical plane, which is inclined with respect to the travel of the cooperating runs of the chains, at an acute angle, and diverges from the direction of the travel of the leaves.

The upper member is composed of a shaft 25 journaled in bearings 26 on the main frame. A hub member or bushing 27 is mounted on the shaft, and a plurality of stripping brushes is supported by the bushing, which is rectangular in cross section, the brushes being supported on the four faces of the bushing. The brushes are arranged in pairs, each pair consisting of a main brush 28, and an auxiliary brush 29, arranged in front of the main brush, and positioned to engage the leaf prior to the engagement of the main brush.

Each of the brushes 28 is carried by a channel shaped member 30, backing against one face of the hub 27, and having an extension 31 fitting that face of the hub which considered with relation to the direction of travel is at the front of the channel member. Each brush 29 is carried by a channel member 32, having extensions 33 and 34 lapping on the extension 31. One of these extensions 34 in the present instance is slotted, and engaged by a screw bolt 35 to adjustably connect the brush to the extension 31.

The brushes 28 are oppositely arranged, and the bristle of each brush are of such length that when the brushes are vertical, the longest bristle of the lowermost brush will be at or above the level of the meeting line of the adjacent runs of the chains 10 and 11. The brushes 29 are so arranged, that when the brushes 28 are in the position just described, the bristles of the brushes will be substan-

tially parallel with those of the brushes 28, but lateral to a plane through the axis of the shaft 25.

The brushes 28-29 cooperate with longitudinal extending ribs 36 which act as stripping edges or blades on a shaft 37 journaled in the main frame below the shaft 25 and parallel therewith. This shaft 37 carries a hub 38 rectangular in cross section, and the carriers for the blades 36 are on opposite faces of the hub. Rounded members 39, segmental in cross section, are arranged on the remaining faces of the hub, the whole constituting a ledger member for cooperation with the brushes. Referring to Fig. 1 it will be noticed that the shafts 25 and 37 are inclined with respect to the direction of travel of the chains 10-11, diverging from the plane of the chains and the direction of travel of the tobacco leaves. The shaft 25 is provided with fast and loose pulleys 40, which may be connected by means of a belt with a suitable source of power. The shaft has a driving connection with the shaft 37 through gear wheels 41.

The shaft 25 also drives a counter shaft 42 journaled in bearing arms 43 at the rear of the main frame, through a miter gear connection 44. The shaft 42 drives the shaft 4 through a miter gear connection 45, and the shaft 12 through a similar connection 46. Thus the shaft drives the chains 10 and 11, the feed belt 5, and the stripping devices.

In order to insure the entrance of the leaves between the stripping devices, that end of the blade carrier adjacent to the chains 10-11 is tapered or conical, and spirally grooved or threaded as indicated at 47, this arrangement tending to feed the leaves into position between the stripping devices.

To facilitate the smooth feeding of the butts from the feed table 5, between the cooperating runs of the chains 10-11, a guide plate and deflector 47^a is connected to the extension at the entrance end of the chains. This guide plate has its lower edge beveled, so that the butts as they pass beneath it are depressed into close contact with the upper run of the lower chain, and guided into position between the chains. Upper and lower sets of guide and guard plates 48 are supported above and below the path traversed by the stem butts as they are carried through the machine, the said plates extending from near the butt plate to near the discharge end of the machine. The plates are supported by threaded stems 49, rotatably connected with the plates, and engaging angle brackets 50. The stems are provided with lock nuts 51^a to hold them in adjusted position.

In order to facilitate the stripping of the lamina from the stem by the stripping devices just described, a primary breaking mechanism is provided in advance of the stripping devices, to break the lamina trans-

versely on each side of the stem, as shown in Fig. 3. The said mechanism comprises a fixed and a rotatable brush, shown more particularly in Fig. 6. The fixed brush consists of a plurality of bristles 51 held in a channel member 52 which has an extension 53 slotted vertically, to permit adjustable connection with the main frame 1. Screws 54 are passed through the slots into engagement with the frame, and it will be evident that when the screws are loosened, the plate and the brush may be adjusted vertically. Normally the free ends of the bristles are at about the level of the meeting line of the adjacent runs of the leaf carrying chains 10 and 11. The brush is spaced away from the chains, a little distance as shown, so that the break made by the brush and the cooperating rotary brush to be described will be spaced a slight distance from the chains.

The rotary brush 55 is secured to a shaft 56 journaled in bearing arms 57^a extending laterally from a bracket 58 forming a part of the main frame, and extending longitudinally thereof. This bracket also supports the bearing arms 43 before mentioned, and the angle plates 50. The shaft 56 is driven by a sprocket chain 57 connecting registering sprocket wheels on the shafts 42, 56, and the bristles of the brushes 51 and 55 are relatively stiff, and adapted to exert a somewhat harsh action on the lamina thereby to insure a clean transverse break of each side of the stem. The engaging surface of the brush 55 moves away from the carrier chains, and the said brush together with the brush 51 will break the lamina transversely in each side of the stem, thereby initiating the stripping operation, which is complete by the stripping devices 28-29-36. The sprocket chain 57 is tensioned by means of a grooved roller 59 journaled on the bracket 58, and engaging the upper run.

The sequence of operations performed on the leaf is shown in Figs. 3, 4 and 5. In Fig. 3 the leaf is shown after it passes the initial breaking mechanism, and it will be noticed, that the lamina 60 of the leaf is broken transversely at 61, on each side of the stem 62, near the butt, the lamina being thus divided into two portions. The stripping devices 28-29-36 strip the lamina on each side of the stem away from the break 61 and toward the tip, leaving the portion above the break intact. Usually cutting mechanism is provided for cutting the main stem near the tip, since the finer portion of the stem is utilized. The lamina thus severed from the stem is discharged, and the stem with the adhering portions 63 is carried on to butt stripping mechanism.

Since the said mechanism operates upon the butt, it is advisable to transfer the stems from the carrier chains 10-11 to other holding mechanism, to permit free access to the

leaf butts. The said mechanism comprises a pair of chains 64 and 65 similar to the chains 10—11, and to which the said chains 10 and 11 deliver. The chains 64 and 65 are so arranged that the lower run of the chain 64 cooperates with the upper run of the chain 65 in the same manner as the adjacent runs of the chains 10—11 cooperate. The forward ends of the chains 64 and 65 are carried by the shafts 12 and 14, while the rear ends are carried by shafts 66 and 67 journaled in the main frame, and parallel with the shafts 12 and 14. The shaft 14 is connected to the shaft 66 by a sprocket chain 68, which engages registering sprocket wheels on the shafts. A tension roller 69 is provided for tensioning the chain 68. Thus the chain 64 is driven, and the chain 65 is driven frictionally thereby. The tobacco leaves are transferred from the chains 10 and 11 to the chains 64 and 65, which are spaced laterally from the plane of the chains 10 and 11, and grasp the stems of the leaves some distance away from the portions 63 of the lamina.

The butt cleaning mechanism is arranged adjacent to the cooperating runs of the chains 64—65, the said mechanism, Fig. 7, comprising a fixed and rotatable brush. The fixed brush 70 is similar to the brush 51, and similarly mounted being adjustably connected with the bracket 58 as indicated at 71. The rotary brush 72 is secured to a shaft 73 journaled longitudinally of the bracket 58. The shaft 73 is driven from the shaft 42 by means of a sprocket chain 74, engaging registering wheels on the two shafts.

A holding plate 75 is arranged on the opposite side of the chains 64—65 from the brushes, the plate being supported by a bracket arm 76 extending from a cross bar 77 which connects a pair of arms 78 supported by the main frame. These arms 78 carry a cross plate 79 at the free ends 45 thereof which are adjacent to the chains 64—65, and the cross plate is directly below the edge of the plate 75, and spaced apart slightly therefrom. Because of the resilient mounting of the plates 75—79, they 50 may move apart from each other to compensate for stems of larger size, or bunched stems, but the said plates tend to hold the stems perpendicular to the plane of the chains, and to the operating line of the 55 brushes. When the portions 63 have been cleaned from the stems, the stems are discharged from the machine.

Means is provided for cleaning the chains 11, 64 and 65. Brushes 80—81 are supported by a common carrier 82 slidably

mounted on pins 83 connected to a bracket arm 84 extending laterally from the bracket 58. Springs 85 encircle the pins between the carrier and the bracket arms. The brushes engage the chains 10—64, and wipe them free from accretion of juice, leaf portions and the like. Another brush 86 is secured beneath the chain 65, and engages the same on the upper run, and at the rear end of the frame.

The preliminary breaking device, serves also another function. There are always stems broken, or weak, which in the usual operation are discarded at some stage in the operation, either because the stem is not of a length, or in proper position to be grasped by the transporting mechanism, or because it is broken or becomes broken before or after it reaches the stripping mechanism. Such discarded leaves are known as "drops," and are usually stemmed manually.

In the present invention, the preliminary breaking mechanism will eject all leaves with defective stems, or stems too weak to withstand the stripping operation, since the action of the preliminary breaker is usually harsher than that of the stripping mechanism, and always sufficient to eject loose or partially loose leaves. Thus the preliminary breaking mechanism is a testing device, 90 for testing the strength of the stems, as to whether or not they are strong enough to pass through the stripping mechanism.

I claim:

1. In a tobacco stemming machine, means 95 to preliminarily separate the leaf lamina transversely of the stem into two portions, and means to strip the portions from the stem, the first named means comprising co-operating fixed and rotating brushes.

2. In a tobacco stemming machine, means to grasp the butts of a succession of leaves and transport them in one direction, means to break the lamina of the leaves transversely of the stems close to the transporting means, means to strip the lamina from the break toward the tip of the leaf, a second transporting means receiving from the first, and arranged to grasp the butts near the break, and a second stripping means for 110 stripping the lamina towards the butts, while the leaves are held by the second transporting means, the breaking means having parts moving at right angles to the direction of travel of the leaves.

Signed at Troy, in the county of Rensselaer and State of New York, this 20th day of April, A. D. 1925.

JAMES P. SCOVILL.
